UNITED STATES PATENT OFFICE.

CARL E. BROWN, OF COLUMBUS, OHIO.

ELECTRIC TRACKER MECHANISM.

Application filed November 15, 1923. Serial No. 674,934.

My invention relates to tracker mechanism for such instruments as player pianos, player organs, or other devices which are operated by means of selected electric circuits, in which a perforated paper strip is passed over a tracker mechanism, with the perforations forming the circuit selecting elements.

In the production of music by electric players, one of the great difficulties has been the quick and positive closing of the desired circuits, since a positive contact to close the selected circuits is a prime requisite. This is indicated in electric player pianos, for example, by a "muddy" effect, of the various notes merging into each other or lagging behind in part.

It is my object to provide a brush and contact mechanism in devices of the type noted which gives firm circuit closures at all times. Among other points of my invention, I provide the tracker bar itself with spaced insulated circuit terminal contact pins, and employ a brush which is common to all circuits, in other words, providing a ground return from electro-magnets, to the brush.

The brush itself forms an important part of my invention, and I form it from a large number of fine wires of conductive material, said wires cut off at the end to form a broad contacting surface, to rest on the perforated roll as it is fed over the tracker. In other words, beside being a brush, according to electric terminology, my device is a wire brush in common terminology. Because of the use of such a mechanism I am able to employ weighting means or some other common means of pressing the brush against the tracker, to the end of assuring contact. In all instances in the past where contact brushes have been formed of bunches of wires for use with tracker mechanisms, each brush has been individual to one circuit, and hence no common weighting mechanism or common mounting mechanism could be used, and the construction has been refined to the extent that a positive operation of the brush at all times has not been possible from a practical point of view.

The use of a brush spanning all contact pins or some substantial number of them, acts in addition as a means for holding the tracker paper down on the tracker bar. The shifting of the paper laterally, where there is an individual brush for each circuit, and

a long contact plate on the tracker, is likely to prevent the brushes from making any contact, which is not possible with a brush extending the whole length of the tracker, and the tracker equipped with individual circuit contact pins, since there will always be a brush contact.

Also in electric player pianos, for example, the requirement is often present for the closing of a number of circuits at the same time, and by my invention this is completely possible while with separate brushes each one acting independently, the exact simultaneous action is not always possible, with the result of the blurring or muddy effect already noted.

I accomplish the objects, and attain the points noted above by that certain construction and arrangement of parts to be hereinafter more specifically pointed out and claimed.

In the drawing:

Figure 1 is a vertical section showing the mechanism.

Figure 2 is a front elevation of the mechanism.

I have shown a tracker bar 1, having a series of insulated contact pins 2, 2, each one forming part of a single electric circuit, as by attachment of wires 3. The pins have contact faces at the top level of the tracker bar. For illustration I have diagrammatically shown an electro-magnet 4, which is connected to wire 3, and also connected to ground 5.

It will be understood that a strip of perforated paper will pass over the tracker, said perforations serving to expose the contact pins to a contact member engaging the paper, directly over the contact surface of the pins.

In its preferred form this member comprises a rock shaft 6, mounted in brackets 7, 7, at the ends of the tracker, and carrying a brush holder 8. This brush holder may be bent over the shaft, and crimped over the wires of the brush. The wires are arranged in the form of a long narrow wire brush, as at 9, the extended assembly of wires being held by the holder. As shown the holder, the shaft or the wires will be grounded, giving to the brush the character of a common return for all circuits that pass through the tracker pins.

The ends of the wires are cut away as at 10 for forming a flat contact, covering an area inclusive of all of the contact pins.

In order to enforce a contact, and prevent the wires of the brush, as they rest on the paper passing over the tracker, from jumping the perforations, and hence not closing the desired circuits, I add a weight mechanism to the brush. This weight mechanism is formed of a heavy rod 11, held in a metal strip 12, which metal strip is riveted to the brush holder. The rod then rests on the wires, and bends them toward the tracker and also acting on the rock shaft, tends to hold the entire brush down against the tracker.

While I might substitute a spring operating on the rock shaft, or some other form of pressure means, the weight form of control has the advantage in addition to that of maintaining contact of actually resting on the wires and keeping them in place, as well as, if desired, partially flexing them from their natural extension from the holder.

I do not desire to be excluded from the doctrine of equivalents in the construction of my claims that follow, because of my failure to point out modified constructions.

Having thus described my invention, what I claim as new and desire to secure by Letters Patent, is:—

1. In combination, a tracker bar, a series of interspaced electric contacts in the tracker adapted to be selectively exposed by a perforated sheet passing over the tracker bar, and a non-selective continuous contact brush to close circuits through said contacts, said brush comprising a single holder and wires in the holder, said wires being arranged to wipe any exposed portion of the tracker bar between the outside contacts.

2. In combination, a tracker bar, a series of interspaced electric contacts in the tracker adapted to be selectively exposed through perforations in a sheet passing over the tracker bar, and a non-selective continuous

contact brush to close circuits through said contacts, said brush comprising a single holder and wires in the holder, said wires being arranged to wipe any exposed portion of the tracker bar within the extreme outside contacts on the tracker bar, and means for impelling the wires on the holder toward the tracker bar to secure a firm engagement and to hold the perforated sheet against the tracker bar.

3. In combination, a tracker bar, a series of interspaced electric contacts in the tracker adapted to be selectively exposed by a perforated sheet passing over the tracker bar and a non-selective contact brush to close circuits through said contacts, said brush comprising a holder and wires in the holder, said wires being arranged to wipe the tracker bar or the perforated sheet thereon over the entire space occupied by said series of contacts, means for pivotally mounting the holder and means for impelling the holder and wires toward the tracker to secure a firm engagement and to hold the sheet down on the tracker, said means comprising a weight mounted so as to tend to swing the holder toward contact position with the tracker.

4. In combination, a tracker bar, a series of interspaced electric contacts in the tracker adapted to be selectively exposed by a perforated sheet passing over the tracker bar, and a non-selective contact brush to close circuits through said contacts, said brush comprising a holder and wires in the holder, said wires being arranged to wipe the tracker bar or the perforated sheet thereon over the entire space occupied by said series of contacts, means for pivotally mounting the holder and a weight suspended against said wires and secured to the holder, whereby the wires are pressed toward the tracker.

CARL E. BROWN.
